TROUBLE LIGHT SUPPORT

Harry L. Martin, 2324 N. Ricketts,
Sherman, Tex. 75090

Filed Sept. 10, 1973, Ser. No. 395,534

Term of patent 14 years

Int. Cl. D26—99
U.S. Cl. D48—4 A

Figure 1

Figure 2

Figure 3

Figure 4

Figure 5

Figure 6

FIG. 1 is a top front left perspective view of a trouble light support in accordance with my new design;

FIG. 2 illustrates a front elevation view;

FIG. 3 is a top plan view;

FIG. 4 is a bottom plan view;

FIG. 5 is a left side elevation view; and

FIG. 6 is a right side elevation view.

I claim:

The ornamental design for trouble light support, substantially as shown.
